(57) **CLAIM**

The ornamental design for a sample carrier, as shown and described.

DESCRIPTION

FIG. 1 is a top front perspective view of a sample carrier showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the sample carrier that form no part of the claimed design.

The dot dash broken lines in the figures depict the boundaries of the claim and form no part thereof.
